UNITED STATES PATENT OFFICE

CHARLES R. GOUDIE, OF KANSAS CITY, MISSOURI, ASSIGNOR TO THE CARNIE-GOUDIE MANUFACTURING CO., OF KANSAS CITY, MISSOURI, A CORPORATION OF MISSOURI

CANVAS HAMMOCK

Application filed May 16, 1930. Serial No. 452,893.

My invention relates to canvas hammocks and like devices including webs adapted to be supported by cords attached to the ends thereof, and requiring spreaders for extending the webs laterally.

In present practice, suspending cords are either fixed to the web fabric or are mounted in grommets adjacent the ends of the web, and spreaders are usually applied to the web 10 independently of the cords. Severe strains are thus put upon the fabric at the points of connection of the cords thereto, and even when the webs are stiffened or strengthened, the strains under use may result in tearing 15 the fabric or distorting the same. Web-attached cords further fail to support the fabric symmetrically unless particular pains are taken to provide spreaders exactly suited to the manner in which the cords are attached 20 to the web, and unless the spreaders are accurately applied.

The use of cords directly connected to hammock webs, and spreaders applied independently of the cords, brings about relatively high cost of manufacturing hammocks due to necessity for threading cords in eyelets or attaching cords to a web, and involves excessive trouble in properly adjusting the 25 hammocks.

The principal objects of my invention therefore are to apply the strain of suspending cords to the spreaders of a hammock, to provide a hammock in which a spreader may be employed for anchoring suspension cords 30 to a hammock web, to distribute the strains of suspension cords over the entire end portion of a hammock, to prevent distortion of a hammock web due to strains or suspension 35 cords, and to facilitate the assembly and use 40 of a hammock including a web, spreaders and suspension cords.

In accomplishing these and other objects of my invention, I have provided improved 45 details of structure, the preferred forms of which are illustrated in the accompanying drawing, wherein:

Fig. 1 is a perspective view of a hammock constructed in accordance with my invention.

Fig. 2 is an enlarged fragmentary perspec-

tive view of a portion of one end of a hammock illustrating the anchoring of a suspension cord by a spreader.

Fig. 3 is a cross section through one of the spreaders and adjacent portion of a web 55 loop in which the spreader is mounted, a suspension cord being shown fragmentarily.

Fig. 4 is a perspective view of a loop portion of a web to form notches in the fold edge of the hem-like portion 4 and provided with 60 a slot for admitting a cord to a spreader.

Referring in detail to the drawing:

1 designates a web or body of a hammock comprising in the illustrated example a sheet or web having back-turned end edge portions 65 2 stitched to the body as at 3 and thus defining an end edge portion 4 to form pockets or loops having sufficient width to freely receive spreaders 5 having notches 6 adjacent their ends.

The loops are provided with a plurality of laterally spaced transverse slots 7 extending longitudinally of the web having edges reinforced by binding 8, whereby the loops or bent portions 9 of cords or ropes 10 may be 75 admitted to and located in a web pocket to receive a spreader inserted in the pocket.

The spreaders preferably comprise wooden sticks having slightly less length than the width of the web, whereby the end of 80 the web loops may be stitched as at 11 to close the ends of the pockets and retain the sticks.

My improved means for connecting cords to a hammock web above described affords 85 opportunity for employment of an improved method of assembling the cord elements, to form the several branches anchored at spaced points by the spreaders, and having outer ends bunched as at 12 and mounted in 90 grooved rings 13 which may be engaged with supporting ropes.

A single cord may be employed for providing the suspending element at one end 95 of a hammock, by the following process:

Hooks may be mounted on a frame or wall in the positions of the portions of a spreader with which cord loops are to be engaged in an assembled hammock. A grooved ring may then be held or suitably supported in 100

a position to receive the outer ends of the cord branches for conferring proper length on the preformed branches to distribute the weight of the hammock.

5 One end of the cord may be tied to the ring, and the cord may be passed back and forth over the hooks and through the ring until all the double ply branches are formed, the free end of the cord then being wrapped 10 around the assembled branches adjacent the ring to form the bunched portion of the cord element, and inserted beneath the encircling coils of the free end to anchor the cord.

15 The loops at one end of the web may then be arranged to locate the outer end loops of the cord in the slots within the pocket, and the spreader may be inserted through the open end of the pocket and moved slidably 20 through the pocket and cord loops to form the anchor for connecting the cord element to the web.

25 In a hammock constructed and assembled as described, the spreaders receive the strains when the rings are connected to supports and the hammock bears a weight, and distributes the strains equally over the fabric comprising the end loops of the web. No 30 stress is put on the fabric due to suspension of the web from the cords, and longitudinal 35 stresses are equally distributed to the several points at which the cords engage the spreaders.

The spreaders will be retained in the pockets due to the closure of the outer ends of 40 the pockets and engagement of the cord loops in the notches of the spreaders, and the cords will be freely slidable on the spreaders to

effect adjustment of tension thereof without involving wearing of the web or tearing stresses thereon.

The frictional effects of cords sliding over fabric or bearing against fabric are thus 70 avoided, and requirement of the use of eyelets to guard fabric openings in which cords are mounted is obviated.

Hammocks constructed in accordance with 75 my invention are easily assembled, are relatively immune to damage to the web under supporting strains, and avoid the formation of longitudinal wrinkles and longitudinal narrow lines of stress produced when suspending cords are inserted through holes 80 in the fabric for directly engaging the web.

What I claim and desire to secure by Letters Patent is:

The method of assembling a hammock including bending a cord to provide a plurality of double ply cord branches of different lengths bunched at one end for attachment to a support, adjusting the lengths of the branches to lengths required for engaging the spreader of the hammock to distribute 90 the weight of the hammock through the branches, inserting the loops at the ends of the branches through slots into a pocket in the end edge of the hammock web, and passing a spreader into the pocket and through 95 the loops to enable the cord branches to engage the spreader directly for supporting the web and closing the ends of the pocket to retain the spreader in said pocket.

In testimony whereof I affix my signature. 100

CHARLES R. GOUDIE.
